ATTORNEY.

UNITED STATES PATENT OFFICE.

HENRY C. SWAN, OF OSHKOSH, WISCONSIN.

STEP FOR VEHICLES.

SPECIFICATION forming part of Letters Patent No. 613,534, dated November 1, 1898.

Application filed July 9, 1898. Serial No. 685,492. (No model.)

To all whom it may concern:

Be it known that I, HENRY C. SWAN, a citizen of the United States of America, residing at Oshkosh, Winnebago county, Wisconsin, 5 have invented certain new and useful Improvements in Steps for Vehicles, of which the following is a specification in such full, clear, and exact terms as to enable any person skilled in the art to which it appertains 10 to make, construct, and use the same.

The annexed drawings and the following description set forth in detail one mechanical form embodying the invention, such detailed construction being but one of various mechanical forms in which the principle of the 15 invention may be used.

In said annexed drawings, Figure I represents a plan view of my improved vehicle-step, which is broken away in part in order 20 to more clearly disclose the construction; and Fig. II, an enlarged detailed view of the joint between the frame and the step-plate.

The forked frame A is provided with a clip a, by which the step may be attached to the 25 vehicle. Each arm of the forked frame is enlarged at its end, forming a flat surface a' circular in outline and having a projection a² upon its face and a recess a³ diametrically opposite said projection. Corresponding flat 30 surfaces b are formed upon the side edges of step-plate B and have a projection b' and a recess b² upon their faces, corresponding to and engaging the recess and projection of the opposed flat surface of the forked frame.

35 Bores a⁴ and d³ are respectively formed through the centers of the flattened portions of the frame and of the step-plate, and a bolt C is inserted through said bores, which suitably secures the opposing surfaces together.

40 To place the step-plate in position, the arms of the forked frame are sprung sufficiently apart to permit the projection on each part to engage the corresponding recess in the opposite part, when they will close together and hold said parts engaged.

45 By means of the construction herein disclosed the step-plate can be quickly and rigidly attached to the forked frame and the step-plate effectually prevented from turning 50 when the step is used. Heretofore steps have

been constructed in two parts, wherein the step-plate rested upon the bent arm or arms of the forked frame and was secured thereto by means of rivets or bolts through the arms of the frame and the bottom or sides of the 55 step-plate. This mode of fastening is clumsy in appearance, and the manufacture of the step is increased in cost. In my improved step the parts can be made of cast metal, and the projections which prevent the step from 60 turning are preferably integral with the parts from which they project, whereby I gain greater simplicity and strength. The parts can be quickly assembled, and I am also enabled to make a neat and finished joint between the arms of the frame and the sides of the 65 step-plate. The rivets or bolts are provided in my device principally for the purpose of preventing the arms of the forked frame from spreading, and the strain upon 70 the step when used is principally exerted upon the integral projections of the forked frame and step-plate.

If a step-plate is broken or is defective, it 75 can be removed by springing the arms of the frame apart, and a new step-plate can be inserted without removing the frame. The step-plate is the part most frequently broken, and the expense of replacing the frame whenever a new step-plate is required is avoided 80 by this construction. Different forms or styles of step-plate can be readily and quickly substituted whenever desirable.

What I claim is—

1. A vehicle-step consisting of a forked 85 frame and a step-plate, one of said parts being provided with a recess, and the other of said parts having a projection said forked frame having sufficient resiliency to adapt it to be sprung upon said step-plate to engage the projection and recess, substantially as set forth.

2. A vehicle-step consisting of a forked frame and a step-plate, each having an engaging portion, said portions being provided with integral interlocking parts the frame 95 having sufficient resiliency to adapt it to be sprung upon said step-plate to engage said parts, substantially as set forth.

3. A vehicle-step consisting of a forked frame and a step-plate, the engaging portions 100

of one arm of said frame and one side of said
step-plate being provided, one with a projec-
tion and the other with a corresponding re-
cess, engaging each other, and means for hold-
5 ing said parts together from lateral displace-
ment, substantially as set forth.

In testimony whereof I sign this applica-

tion, in the presence of two witnesses, this
29th day of June, 1898.

HENRY C. SWAN.

Witnesses:

G. H. FOSTER,
G. M. WILKINS.
